[57] CLAIM

The ornamental design for a static pressure control
assembly for environmentally controlled buildings and
the like, substantially as shown and described.

DESCRIPTION

FIG. 1 is a front perspective view of a static pressure
control assembly for environmentally controlled build-
ings and the like, showing my new design;

FIG. 2 is a front elevational view thereof;

FIG. 3 is a side elevational view thereof, viewed from
the left of FIG. 2;

FIG. 4 is a rear elevational view thereof; and

FIG. 5 is a bottom view thereof.
